JULIUS RITTER, JR., OF RACINE, WISCONSIN, ASSIGNOR TO HARTMANN TRUNK COMPANY, OF RACINE, WISCONSIN, A CORPORATION OF WISCONSIN

TRUNK AND SUITCASE VALANCE

Application filed September 13, 1928. Serial No. 305,758.

This invention relates to improvements in trunk or suitcase valances.

In the ordinary valance construction the side flanges are of an equal length and engage the edge portions of a trunk wall an equal distance on both sides. Consequently, the securing means for the valance, usually rivets, must extend through both valance flanges and the interposed wall. The use of 10 rivets for this purpose is comparatively expensive and the riveting process is somewhat slow.

It is, therefore, the primary object of the present invention to overcome the above objection by providing a trunk or suitcase valance in which one flange is considerably shorter than the other, whereby nails or pins may be used for the valance securing means, it being necessary for the securing means to 20 pass through only one thickness of metal and the trunk wall, and this arrangement reduces the expense of the valance securing means, reduces the time consumed in the attachment of valances, and provides for a thinner wall 25 edge.

A further object of the invention is to provide a trunk valance extending around the adjacent edge portions of the walls of the trunk sections and forming a practically dust 30 and water proof tongue and groove joint between the sections.

A further object of the invention is to provide a trunk or suitcase valance which is of very simple construction, is inexpensive, is 35 strong and durable, and is well adapted for the purposes described.

With the above and other objects in view the invention consists of the improved trunk or suitcase valance, and its parts and combinations as set forth in the claim, and all equivalents thereof.

In the accompanying drawings in which the same reference characters indicate the same parts in all of the views:

45 Fig. 1 is a vertical sectional view of a small trunk or wardrobe suitcase with the sections opened with respect to each other, the edge portions being provided with the improved valance;

50 Fig. 2 is an enlarged fragmentary detail

sectional view showing a pair of meeting walls and the improved valance forming a joint between the wall edges;

Fig. 3 is an enlarged fragmentary detail view of a section corner and the valance arrangement;

Fig. 4 is a fragmentary view of a section corner showing a slightly modified form of valance therefor; and

Fig. 5 is a similar view with one portion 60 of the valance corner removed to show details of construction.

Referring now more particularly to the drawings, it will appear that the numeral 8 indicates a wardrobe suitcase having a pair 65 of complementary sections 9 and 10 adapted to be opened and closed with respect to each other.

The outer edge portions of the walls 11 of the section 10 are adapted to meet the 70 outer edge portions of the walls 12 of the section 9, when the sections are closed with respect to each other, and to form a dust and water-proof tongue and groove joint between said adjacent edges, the improved valance construction is provided.

The walls of one of the sections, as 10, are provided with a tongue valance, generally indicated by the numeral 13, while the walls of the other section 9 carry a groove valance 80 14.

Referring particularly to Fig. 2 it will be seen that the tongue valance comprises an elongated strip of metal for the outer edge of each wall 11 and said strip is bent to form a protruding elongated 85 tongue 15 of double thickness with a slightly outwardly off-set long outer wall face flange 16, and a comparatively short slightly off-set inner wall face flange 17. The flanges 16 and 17 embrace the outer edge portions of the outer and inner faces, respectively, of a wall 11 and the attaching means comprise pins 18 extended through the outer flange 16, the veneer board layers of the wall, and are then bent over, as at 19, against the inner surface 95 of said wall. Because of the short flange 17 the pin only has to extend through one thickness of valance metal and yet the valance is adequately secured, and the bent over portions 19 of the pin do not protrude beyond the 100 top

thickness of the flange 17. The inner surfaces of the walls 11 may be covered by a lining material 20, while a fabric strip 21 also embraces the outer edge portions of said 5 walls inwardly of the valance.

The groove valance 14 for the walls 12 of the section 9 is also formed of elongated strips of metal, each strip being bent to form a central U-shaped groove portion 22 with 10 a long flange 23 for the outer face of a wall 12 and a short flange 24 extending inwardly therefrom for the inner face of a wall 12. The securing means is the same as that described for the tongue valance 15, consisting 15 of light pins 18 extending through the outer face long flange, the wall veneer layers, and bent over at 19 against the inner surface of the wall inwardly of the short flange. Also 20 between the valance of the wall is a wall edge embracing fabric strip 21 and the inner surfaces of the walls have linings 20.

The valance arrangement for a corner is illustrated in Fig. 3 wherein the veneer plies of the walls 12 meet at right angles and an 25 outer curved re-enforcing band 25 is provided. The valance members 14 terminate short of the junction of the walls. While the corner construction for a groove valance has been shown, the tongue valance corner arrangement is carried out in the same way. 30

In Figs. 4 and 5 a modified form of corner construction and the valance arrangement therefor has been illustrated. The corner is 35 of the re-enforced type, wherein the veneer plies 11 extend into a corner post member 26, and the latter is covered externally by a fabric leather or composition band 29. A short intermediate curved valance member 27 is mounted on the upper outer edge portion of 40 the post 26 and the end portions of said member 27 are slightly reduced, as at 27'. The two adjacent walls 11 are covered by an integral valance member 13'', which, at its mid- 45 portion is cut-away, so that only the long outer flange portion remains forming an outer curved strap 28 which engages the outer surface of the member 27. The tongue portions 15' of the valance slightly overlap 50 the reduced portions 27' of the member 27 and hold said member firmly in position. The valance 13'', as in the principal form, has a long outer flange and a short inner flange and the securing means extends only 55 through the long flange thereof and the wall. This corner valance construction just described has the advantage over the other arrangement, in Fig. 3, in that the valance is continuous. The valance shown in Figs. 4 60 and 5 is of the tongue type, but the grooved valance may be arranged the same way for corners.

From the foregoing description it will be 65 seen that the improved valance construction for trunks, suitcases, or the like is both sim-

ple and novel, and is well adapted for the purposes described.

What I claim as my invention is:

In a two-section container, the adjacent edge portions of the section walls being in 70 juxtaposition when the sections are closed with respect to each other, grooved valance members mounted on the outer edge portions of the walls of one section, and tongue valance member mounted on the outer edge 75 portions of the walls of the other of said sections, said tongue and groove valance members being inter-fitting, each valance member having spaced apart sides engaging opposite surfaces of the section wall and its outer 80 side being considerably longer than the other, and headed, bendable metallic securing pins extended through only the long outer sides of the valance members, and the respective section walls and having their end portions bent over against the inner surface of the walls substantially flush with the short inner sides of the valance members.

In testimony whereof, I affix my signature.
